Primary Examiner — Mary Ann Calabrese*Assistant Examiner* — Catherine Ho(74) *Attorney, Agent, or Firm* — Muirhead and Saternelli, LLC(57) **CLAIM**

The ornamental design for a rollaway toolbox, as shown and described.

DESCRIPTION

FIG. 1 is a perspective view of a rollaway toolbox showing the new design.

FIG. 2 is a front view thereof.

FIG. 3 is a rear view thereof.

FIG. 4 is a left side view thereof.

FIG. 5 is a right side view thereof.

FIG. 6 is a top plan view thereof; and,

FIG. 7 is a bottom plan view thereof.

The broken line portion of the figure drawings is included to show portions of the article that form no part of the claimed design.

1 Claim, 7 Drawing Sheets(56)
